AIRPLANE

John R. Clark, Lyman C. Josephs III, and Conrad A. Lau,
Dallas, Tex., assignors, by mesne assignments, to
Chance Vought Aircraft, Incorporated, a corporation
of Delaware

Application February 2, 1953, Serial No. 23,402

Term of patent 7 years

(Cl. D71—1)

Fig. 1

Fig. 2

Fig. 3

Fig. 4

Fig. 5

Fig. 1 is a top plan view of the airplane, showing our new design;

Fig. 2 is a side elevational view;

Fig. 3 is a front elevational view;

Fig. 4 is a perspective top view, looking down on the airplane from the left front; and

Fig. 5 is a rear view of the airplane.

The essential features of our design reside in the portions shown in full lines.

We claim:

The ornamental design for an airplane, substantially as shown and described.
